CLAIM

The ornamental design for a humidifier heaterbase as shown and described.

DESCRIPTION

FIG. 1 is a top, front and side perspective view of a humidifier heaterbase embodying our new design.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

Broken lines are used to illustrate features of the humidifier heaterbase which form no part of the claimed design. The dot dot dash line represents a boundary line and forms no part of the claimed design. The break lines indicate that any portion of the humidifier heaterbase between the break lines forms no part of the claimed design.
